UNITED STATES PATENT OFFICE

153,966

DESIGN FOR A TABLE ORNAMENT OR SIMILAR ARTICLE

Laurance McDougall, Goliad, Tex.

Application October 18, 1946, Serial No. 134,040

Term of patent 14 years

(Cl. D29—1)

To all whom it may concern:

Be it known that I, Laurance McDougall, a citizen of the United States, resident at Goliad, in the county of Goliad and State of Texas, have invented a new, original, and ornamental Design for a Table Ornament or Similar Article, of which the following is a specification, reference being made to the accompanying drawing, forming a part thereof.

The single figure of the drawing is an elevational view of the table ornament or similar article, showing my new design.

The design is of a conical shape and the opposite side is similar to that shown.

I claim:

The ornamental design for a table ornament or similar article, substantially as shown and described.

LAURANCE McDougall.
